FLUID BURNER CONTROLLER

Laurence M. Perkins, Syracuse, N. Y., assignor to
 Carrier Corporation, Newark, N. J., a corpora-
 tion of Delaware

Application August 11, 1937, Serial No. 158,460

11 Claims. (Cl. 158—36)

This invention relates to combustion devices such as oil burners and more particularly to an improved method of and apparatus for controlling the operation thereof.

When oil or any other fuel is burned, it is essential, if greatest operating efficiency is to be obtained, that a minimum of excess air be supplied for combustion. This follows from the fact that the excess air supplied does not enter into chemical combustion with the fuel and therefore does not foster the liberation of heat, but serves merely to carry away heat units from the combustion chamber, to increase the stack loss, and thus to detract from the efficiency of the burner device. On the other hand, if an insufficient quantity of air is supplied, the oil or other fuel will not be completely burned and some of it will be deposited as soot while another portion of the fuel may escape up the chimney without having been burned. This operating condition also results in inefficiency.

When the flame of an oil burner is first started, the chimney is cold. Thus, there is relatively little draft with the result that less air is supplied to the combustion chamber than after the chimney has become heated and the draft increased thereby. Also, when oil is cold, as it usually is prior to the operation of an oil burner, it has a higher viscosity than when it is warm. The spray nozzles which are commonly used with pressure type oil burners are so constructed as to deliver a larger quantity of oil at a given pressure when the oil has a high viscosity than when the oil has a lower viscosity. Accordingly, when an oil burner is started, both the relatively low draft and the relatively high oil viscosity tend to decrease the ratio of air to oil, and thus tend to cause soot deposit and incomplete combustion of the fuel. To provide efficient operation, therefore, it is necessary to vary this ratio so that the oil and air are in desired proportions at all times. This may be accomplished by reducing the amount of oil supplied to the burner during starting-up periods.

After the oil burner has been operating for a short time, the chimney has become heated, the draft increased, and hence there is a greater supply of air to the combustion chamber. Then oil may be supplied to the combustion chamber at a greater rate than during the starting-up period.

When it is realized that in conventional applications oil burners frequently go on and off several times an hour throughout the day, or even more frequently, there will become apparent the importance of providing for efficient combustion during both normal operating and starting-up periods, and of preventing the deposit of soot.

The object of this invention is to provide for

the supply to the combustion chamber of a fluid burner device of fuel and air in desired proportions both during starting-up periods and during periods of normal operation, to insure high operating efficiency and to prevent soot deposit. 5

Another object of the invention is to provide a method of and apparatus for supplying fluid fuel to a burner at a relatively low rate during starting-up periods and at a greater rate during periods of normal operation following the starting-up periods.

It is another object of the invention to provide a fuel control device for fluid burning devices such as oil burners, which is adapted automatically to provide for optimum conditions of combustion during all periods of operation, whereby the operating efficiency of the device may be increased, the cost of operation minimized, and the cost of maintenance substantially reduced. 15 20

According to present practice, it is customary in supplying oil to the nozzle of an oil burner device to pump a considerable quantity of oil from an oil supply tank. This oil is supplied to a pressure regulating valve which is designed to maintain a substantially constant predetermined pressure within the pipe leading to the nozzle whenever the oil burner is operative, and to positively close the oil passage leading to the nozzle whenever the oil burner becomes inoperative. Of the total volume of oil supplied to the pressure regulating valve, a relatively small portion only is supplied to the nozzle, the remainder of the oil being circulated through the pressure regulating valve and then returned through a bypass line to the oil supply tank. 25 30 35

According to the invention, there is provided a valve in the bypass line of the arrangement just described for restricting the flow of fuel through the bypass line.

When the valve in the bypass line restricts flow therethrough to a relatively great extent, pressure is developed in the fluid circulating system back of the valve. This increase in pressure, transmitted through the pressure regulating valve, affects the pressure in the pipe leading to the nozzle, and as the pressure in this pipe is increased, the rate at which fluid is discharged therefrom increases. When the valve in the bypass line restricts flow therethrough to a lesser extent, the pressure within the fluid circulating system is less than in the case of greater restriction of the bypass line. Accordingly, in such case, the fluid pressure in the circulating system back of the valve and in the pipe leading to the nozzle is lower and fluid is discharged from the nozzle at a lower rate. 40 45 50 55

Accordingly, a feature of the invention resides in providing flow control means, such as a valve, for variably restricting fluid flow through a bypass line through which fluid is returned from 60

the pressure regulating valve of an oil burner oil circulating system to the oil tank thereof.

Other objects, features and advantages of the invention will be more apparent from the following description to be read in connection with the accompanying drawing, in which:

Fig. 1 diagrammatically represents an oil burner system embodying the invention, and

Fig. 2 diagrammatically represents an oil burner system embodying a modified form of the invention.

Referring now to the drawing, the numeral 10 designates an electrical motor driving a fan 11 adapted to discharge air through casing 12 into a combustion chamber generally designated 13. Motor 10, through a drive chain 14 or other suitable means, is adapted to drive oil pump 15 which draws oil from oil supply tank 16 through line 17 and supplies it through line 18 to a pressure regulating device generally designated 19. Oil supply line 20 supplies oil from pressure regulating device 19 to oil discharge nozzle 21 located within the path of air discharged from casing 12. 22 designates a spark device for igniting oil discharged from nozzle 21. Spark device 22 may be of any desired type or construction and may be connected to a suitable source of electrical energy in any desired manner, and since the construction and operation of such devices are well known in the art, no further description of device 22 is deemed necessary here.

Connecting with the pressure regulating device 19 is a bypass line generally designated 23, adapted to return oil from the pressure regulating device to the oil supply tank 16. Interposed in the line 23 is an auxiliary valve generally designated 24. For convenience, that portion of line 23 which lies between the valves 19 and 24 is designated 23a and that portion of the line 23 which lies between the valve 24 and tank 16 is designated 23b. Pressure regulating device 19 is provided with a partition 25 which is formed with an opening 26 and an auxiliary opening 27. Extending through opening 26 is a double ended 45 valve member of the needle valve type designated 28. One end of member 28 is adapted to control the supply of fluid to line 20 through port 29 formed at an end of the pressure regulating device. A spring 30 operating against a flange 31 formed on valve member 28 tends to force the valve member 28 away from port 29. The opposite end of valve member 28, which extends through opening 26, is adapted to control fluid flow through a port 32 formed in plate 33. 55 Plate 33 is carried upon bellows 34, the bellows being secured to the inside of pressure regulating device 19. A spring 35 tends to force plate 33 toward partition 25. Preferably, a screw regulating device 36, extending through the casing 60 of the pressure regulating device, is provided to control the pressure exerted by spring 35 on the plate 33. The pressure of spring 35 is greater than that of spring 30. Thus, when the system is inoperative, as during shut-down periods when 65 the oil pump 15 is not operative, spring 35 will force the plate 33 against member 28 and force member 28 to close port 29.

Valve 24 includes a valve chamber 37 within which is disposed a valve member 38 carried 70 upon and actuated by a sylphon bellows 39 attached to the valve casing. The interior of bellows 39 is connected through line 40 with a thermal element 41. Thermal element 41 is adapted to be heated by an electrical heating coil 42 which 75 is adapted to be energized whenever the motor

10 is energized, i. e., whenever the burner device is operative. The heating coil 42 may be connected in series with the motor 10 or in parallel therewith, as shown. The switch means controlling the energization of the electrical circuits, 5 diagrammatically designated 10a, is preferably connected in series with the heating coil 42 and the motor 10 so that only one switch need be provided. Of course, if the motor 10 and heating coil 42 are connected in parallel with each other, then two separate switches, one in each of the individual parallel circuits, may be provided if desired. The switch means is preferably controlled responsive to variations in the temperature of a room or the like heated by 15 the device, by means of a suitable thermostatic control. Since such control is old and familiar in the art, no further description of this feature is deemed necessary here.

In operation, the fan 11 and the pump 15 are 20 rendered operative by the energization of motor 10, fan 11 then discharging air through casing 12 into combustion chamber 13. Oil pump 15 draws oil from supply tank 16 and delivers it through line 18 to the pressure regulating device 25 19. The oil passes through opening 27 and thus builds up a pressure within the chamber 43 which forces the plate 33 backward against the pressure of spring 35. As the plate 33 moves to the right, the valve member 28 follows the plate under the influence of spring 30 and thus provides communication between the chamber 44 and the oil supply line 20 through port 29, whereby oil is delivered to the nozzle 21. The motion of valve member 28 to the right is limited by a collar 45 35 adapted to engage partition 25. As the oil pressure in chambers 44 and 43 continues to build up, the port 32 is opened, whereupon oil flows from chamber 43 through the interior of the bellows 34 and thence through line 23. All of these operations take place within a 40 second or two after the oil pump begins to operate.

Since the heating coil 42 at this time is relatively cold, due to the fact that the oil burner has been inoperative and the operating period 50 has just commenced, the fluid within the thermal element 41, the line 40 and bellows 39 is in relatively contracted condition. Thus, the valve member 33 is, at the commencement of an operating period, in such position as to restrict to 55 a relatively slight degree only oil flow through line 23.

However, as the oil burner continues in operation, the energization of the heating coil 42 continues to heat the fluid within the thermal element 41 and the bellows 39 is accordingly expanded. Thus, the valve member 33 is caused increasingly to restrict oil flow through the line 23. As will be understood, the restricting effect of valve 33 causes a pressure to be built up in 65 valve chamber 37 and in line 23a. This pressure is transmitted in turn to the interior of bellows 34 and through port 32 into chamber 44 and thus to the oil supply line 20. The increased oil pressure in line 20 results, in turn, in increased delivery of oil from the supply nozzle. In this way the pressure in the oil supply line 20 is controlled by variations of pressure in line 23.

As will be understood, the restrictive action 75

of valve 38 increases as the pressure within the bellows 39 builds up, or in other words, as the oil burner device continues in operation. Thus, the oil pressure in the oil supply line 20 begins 5 to increase immediately following the time when the oil burner becomes operative. The pressure in bellows 39 stops rising when, after a time, the heat dissipated from the thermal element equals the heat input thereto, following which 10 the pressure in chamber 37 and in line 23a remains substantially constant. Accordingly, the pressure in chamber 44 and in supply line 20 also reaches a corresponding maximum point, at which the pressure remains constant throughout the remainder of the operating period.

When the oil burner is rendered inoperative, the heating coil 42 is deenergized and valve member 38 is gradually moved away from its seat. Also valve member 28 closes port 29 under the 20 influence of spring 35. Thus the apparatus is adapted to operate as above described upon the commencement of the next operating period.

In Fig. 2, the heating coil 42 is dispensed with and the thermal element 41 is located within the 25 combustion chamber 13. Thus, as the oil burner continues to operate, the fluid in thermal element 41 continues to be heated, whereby desired control of the oil supply is effected substantially as described in connection with Fig. 1. It will 30 be understood that the thermal element need not be placed within the combustion chamber, but may be located at any desired point where it is heated by operation of the burner, as, for example, in the stack.

Thus, it will be seen that during the period during which the oil burner is beginning to operate the oil pressure in the oil supply line is relatively low, and hence there is a relatively small quantity of oil delivered therefrom. But as the 40 burner continues to operate, the pressure in the oil supply line leading to the discharge nozzle (and hence the rate of oil discharge from the nozzle) is increased, until it reaches a predetermined and constant maximum value, the oil 45 pressure remaining at this point until the operation of the oil burner is interrupted.

As will be understood, the pressure in chamber 44, and hence the pressure in line 20, is determined in accordance with pressure differential 50 across plate 33, and this pressure differential is directly controlled by the pressure exerted by the spring 35. It will be seen, therefore, that the pressure in the oil supply line 20 may be regulated by adjustment of regulating device 36, 55 which controls the pressure exerted by spring 35.

Since many modifications may be made in the invention without departing from the scope thereof, it is to be understood that the foregoing description and accompanying drawing are intended as illustrative only, applicant limiting himself only as indicated in the appended claims.

I claim:

1. In a fluid burner device adapted to be intermittently operative, a source of fluid fuel, a burner, a pressure regulating valve serving said burner at all times during operation of the latter, means for supplying fuel from said source to said valve, means constantly supplying to said burner from said valve a portion only of the fuel supplied to said valve, means constantly returning to said source of fuel from said valve another portion of the fuel supplied to said valve, auxiliary valve means for controlling said return of fuel to said source and for controlling the pressure at which fuel is supplied to said burner from

said first-mentioned valve, a thermal element, means for heating said thermal element responsive to operation of the device, and means responsive to heating of said thermal element for decreasing to a predetermined point the effective 5 opening of said auxiliary valve means.

2. In a fluid burner device adapted to be intermittently operative, a source of fluid fuel, a burner, a pressure regulating valve serving said burner at all times during the operation of the latter, means for supplying fuel from said source to said valve, means constantly supplying to said burner from said valve a portion only of the fuel supplied to said valve, means constantly returning to said source of fuel from said valve another portion of the fuel supplied to said valve, auxiliary valve means for controlling said return of fuel to said source and for controlling the pressure at which fuel is supplied to said burner from said first-mentioned valve, a thermal element, 10 means for heating said thermal element responsive to operation of the device, and means responsive to heating of said thermal element for restricting flow through said auxiliary valve means subsequent to the commencement of a burner operating period so that fuel is thereafter supplied to said burner from said pressure regulating valve at a predetermined pressure.

3. In a fluid burner device adapted to be intermittently operative, a source of fluid fuel, a burner, 30 a pressure regulating valve controlling the supply of fuel to said burner at all times during the operation of the latter, means for supplying fuel from said source to said valve, means constantly supplying to said burner from said valve a portion only of the fuel supplied to said valve, means constantly returning to said source of fuel from said valve another portion of the fuel supplied to said valve, auxiliary valve means for controlling said return of fuel to said source and 35 for controlling the pressure at which fuel is supplied to said burner from said first-mentioned valve, a thermal element, a heating coil adapted to heat said thermal element, means for rendering operative said heating coil whenever said device is operative, and means responsive to heating of said thermal element for restricting flow through said auxiliary valve means.

4. In a fluid burner device adapted to be intermittently operative, a source of fluid fuel, a burner, 50 a pressure regulating valve controlling the supply of fuel to said burner at all times during the operation of the latter, means for supplying fuel from said source to said valve, means constantly supplying to said burner from said valve a portion only of the fuel supplied to said valve, means constantly returning to said source of fuel from said valve another portion of the fuel supplied to said valve, auxiliary valve means for controlling said return of fuel to said source 55 and for controlling the pressure at which fuel is supplied to said burner from said first-mentioned valve, a thermal element adapted to be heated by combustion of fuel within the device, and means responsive to heating of said thermal 60 element for restricting flow through said auxiliary valve means.

5. In combination with a fluid burner device including a source of fuel, a burner, a pressure regulating valve serving said burner and controlling the supply of fuel thereto at all times during the operation of said burner, means for supplying fuel from said source to said pressure regulating valve, means constantly supplying to said burner a portion only of the oil supplied to

- said valve, and means constantly returning to said source the remaining portion of oil supplied to said valve; auxiliary valve means for restricting the flow of fuel from said valve to said source and for regulating the pressure at which fuel is supplied from said valve to said burner, means for operating said valve, and means for controlling said operating means responsive to operation of the device, said control means and said operating means being adapted and arranged to restrict fluid flow through said auxiliary valve means following the commencement of a burner operating period, whereby to increase the pressure at which fuel is supplied to said burner to a predetermined point, said control means and said operating means being adapted and arranged thereafter, during the remainder of the operating period, to maintain such restriction of said auxiliary valve means to maintain said fuel pressure at said predetermined point.
6. In a fluid burner device adapted to be intermittently operative, a source of fluid fuel, a burner, a pressure regulating valve serving said burner and controlling the supply of fuel thereto at all times during the operation of said burner, means for supplying fuel from said source to said valve, means constantly supplying to said burner from said valve a portion only of the fuel supplied to said valve, means constantly returning to said source of fuel from said valve another portion of the fuel supplied to said valve, auxiliary valve means for controlling said return of fuel to said source and for controlling the pressure at which fuel is supplied to said burner from said first-mentioned valve, a pressure-responsive element, means for actuating said pressure-responsive element responsive to operation of the device, and means responsive to actuation of said pressure-responsive element for restricting fluid flow through said auxiliary valve means.
7. In an apparatus of the character described, a source of fluid fuel, a burner, a pressure regulating valve serving said burner at all times during operation of the latter, means for supplying fuel from said source to said valve, means constantly supplying to said burner from said valve a portion only of the fuel supplied to said valve, means constantly returning to said source from said valve another portion only of the fuel supplied to said valve, auxiliary valve means for controlling said return of fuel to said source and adapted to control the pressure at which fuel is supplied to said burner from said first-mentioned valve, and means for restricting fuel flow through said auxiliary valve means to a predetermined limit following initiation of a burner operating period.
8. In a fluid burner device adapted to be intermittently operative, a source of fluid fuel, a burner, a pressure regulating valve serving said burner at all times during operation of the latter, means for supplying fuel from said source to said valve, means constantly supplying to said burner from said valve a portion only of the fuel supplied to said valve, means constantly returning to said source of fuel from said valve another portion only of the fuel supplied to said valve, auxiliary valve means for controlling the return to said source of said other portion of the fuel and adapted to control the pressure at which fuel is supplied to said burner from said first-mentioned valve, and means for causing said auxil-

5
ary valve means to restrict, to a predetermined limit, the flow of fuel being returned to said source responsive to the lapse of time subsequent to the commencement of a burner operating period.

9. In a fluid burner device adapted to be intermittently operative, a source of fluid fuel, a burner, a pressure regulating valve mechanism including a first valve and a second valve, said mechanism serving said burner at all times during operation of the latter, means for supplying fuel from said source to said valve mechanism, means including said first valve constantly supplying to said burner from said valve mechanism a portion only of the fuel supplied to said valve mechanism, means including said second valve constantly returning to said source of fuel from said valve mechanism another portion only of the fuel supplied to said valve mechanism, auxiliary valve means for controlling said return of fuel to said source and adapted to control the pressure at which fuel is supplied to said burner from said valve mechanism, and means responsive to continued operation of the burner for causing said auxiliary valve means to restrict the flow of fuel returning to said source to a predetermined limit following the initiation of a burner operating period.

10. In a fluid burner device adapted to be intermittently operative, a source of fluid fuel, a burner, a pressure regulating valve controlling the supply of fuel to said burner and serving said burner at all times during the operation of said burner, means for supplying fluid fuel from said source to said valve, means at all times during the operation of said burner supplying to said burner from said valve a portion only of the fuel supplied to said valve, means at all times during the operation of said burner returning to said source from said valve another portion of the fuel supplied to said valve, means for controlling the return to said source of said last-mentioned portion of the fuel and adapted to control the pressure at which fuel is supplied to said burner from said valve, and means for causing said control means to restrict the flow of fuel returning to said source responsive to continued operation of the burner subsequent to the commencement of a burner operating period.

11. In an apparatus of the character described, a source of fluid fuel, a burner, a pressure regulating valve mechanism serving said burner at all times during operation of the latter, means supplying fuel from said source to said valve mechanism, means constantly throughout a burner operating period supplying to said burner from said valve mechanism a portion only of the fuel supplied to said valve mechanism, means constantly throughout a burner operating period returning to said source from said valve mechanism another portion only of the fuel supplied to said valve mechanism, auxiliary means for controlling said return of fuel to said source and adapted to control the pressure at which fuel is supplied to said burner from said valve mechanism, and means in control of said last-mentioned auxiliary means for restricting to a predetermined limit, following initiation of a burner operating period, the return of fuel from said valve mechanism to said source of fuel.

LAURENCE M. PERKINS.
